UNITED STATES PATENT OFFICE.

HENRY E. DERBYSHIRE, OF CHAMBERSBURG, PENNSYLVANIA, ASSIGNOR TO CHAMBERSBURG ENGINEERING COMPANY, OF CHAMBERSBURG, PENNSYLVANIA, A CORPORATION OF PENNSYLVANIA.

HAMMER CONSTRUCTION.

1,077,812.

Specification of Letters Patent.

Patented Nov. 4, 1913.

Application filed November 1, 1911. Serial No. 657,938.

To all whom it may concern:

Be it known that I, HENRY E. DERBYSHIRE, a citizen of the United States, and a resident of Chambersburg, Franklin county, Pennsylvania, have invented certain Improvements in Hammer Constructions, of which the following is a specification.

My invention relates to improvements in the frame and anvil construction of hammers particularly designed for drop forge work and of the type in which the frames rest on and are bolted to the anvil.

In hammers of the above noted type, it has been found difficult to obtain large anvil castings which were sound and free from shrinking strains and at the same time of the proper construction to successfully withstand the heavy duty required of them.

One object of my invention, therefore, is to so construct the frame and anvil that the latter shall be capable of resisting the strains to which it is subjected and particularly shall be of such a form as to resist a tendency to breakage.

I further desire to provide a form of hammer construction which, while being capable of successfully withstanding the heavy work for which it is intended, shall have an anvil of relatively great depth, with the bolts connecting the frame and the anvil so disposed that there shall be no recesses or pockets which might serve as the starting point for cracks.

The objects and other advantageous ends I attain as hereinafter set forth, reference being had to the accompanying drawings, in which:—

Figure 1, is a front elevation of a hammer constructed according to my invention; Fig. 2, is a side elevation of the anvil and frame shown in Fig. 1; Fig. 3, is a half plan of the anvil; Figs. 4 and 5, are horizontal sections taken respectively on the lines *a—a*; *b—b*; Fig. 1; Fig. 6, is a fragmentary horizontal section of a portion of a hammer in which adjustable guides are employed; Fig. 7, is a slightly modified form of an anvil; Figs. 8 and 9, are respectively a front and a side elevation of a form of hammer in which the anvil and frame are integral and Figs. 10 and 11, are respectively a front and side elevation of a slightly modified form of hammer.

In Figs. 1 to 5 of the above drawings, 1

represents the anvil and 2 the side frames of a drop hammer; said frames having formed in their adjacent faces relatively deep grooves fitted on correspondingly formed tongues 3 of the anvil. This latter is also provided with transverse ledges 4 on which rest the lower ends of the side frames and these latter are clamped together and to the upper tongued portion of the anvil indicated at 1^a by two sets of bolts 5 and 6 so placed as to extend clear of the anvil. These bolts 5 may be shrunk into place or tightened up in the usual way so as to constitute a reinforcement of or addition to the strength of the anvil so as to assist in resisting the strains which occur therein. 70

In order to hold the side frames down on the anvil so as to resist the lifting strains due to the rebound when a blow is struck by the head or ram, I provide dowel pins 7 in the sides of the anvil extension 1^a, fitting 75 in suitably formed recesses in the adjacent faces of said side frames.

The top portions of the side frames are held together by tie plate 8, lipped over or recessed for the reception of said ends which are also clamped together by bolts 9. This top plate is also upwardly flanged or lipped to assist in holding in place the structure 10 constituting the cylinder casting in which operates the piston whose rod 11 is attached 85 to the ram 12. This latter is longitudinally recessed as shown in Fig. 4 for the reception of guides formed integral with the side frames 2 though, if desired, in some instances I may recess said side frames as at 90 2^a in Fig. 6, and mount in said recesses adjustable guides 13.

The cap 14 is mounted on the top of the anvil extension 1^a and its opposite ends are flanged or downwardly lipped as indicated 95 in Fig. 2 so as to fit over the sides of said extension. Moreover, the side frames are undercut adjacent this cap 14, as indicated at 15 and 16, and the cap is upwardly tapered so that a key 17 driven between it 100 and one of the side frames cooperates with the other side frame to hold it in place on the anvil. Both the cap and ram are notched for the reception of dies which may be of any desired form. 105

In place of the dowel pins 7 I may form an extension of the upper portion of the anvil as indicated at 1^b, Fig. 7, making it

taper downwardly toward the body or main portion of the anvil and shaping the lower portions of the side frames so that they fit the extension, with the result that their 5 tendency to lift, under operating conditions, is effectually resisted.

In that form of my invention shown in Figs. 8 and 9 each of the side frames 2^a is formed integral with one-half of the anvil 10 and in this instance there is a vertical joint, lying in the median plane of the hammer, between the two halves of the anvil portion. Said two halves are clamped together by two pairs of bolts 5^a and 6^a of which the upper set extends clear or outside of the part 15 of the structure which corresponds to the upwardly projecting anvil extension. This latter is provided with an under cut recess whose sides are formed by the lower portions 20 of the side frames, for the reception of the cap which, as previously shown, is flanged at its end so as to closely fit the anvil extension and also has a key 17 serving to hold it in place. Dowel pins 7^a connect 25 the lower portions of the two castings, of which each is formed of one of the side frames and half of the anvil; there being also a transversely extending tongue 7^b on one of the anvil halves, designed to closely 30 fit a recess of corresponding form in the other half of the anvil.

Another form of my invention is shown in Figs. 10 and 11 in which, as in the case shown in Figs. 1 and 2, the anvil consists 35 of a main body portion 1^a and an extension 1^c. The side frames 2^b rest upon or are mounted in ledges in the upper portion of the anvil and in this case are clamped together by a single pair of bolts 5^b which 40 pass through openings in the anvil extension 1^c. The cap 14 has its lower portion upwardly tapered and is held to the undercut lower portions of the side frames by a key 17, as previously described. In any case, however, 45 it is to be noted that the anvil is of a relatively deep construction; that the joints between its parts or between it and the side frame partially or wholly consist of meeting faces which lie in substantially vertical 50 planes. The parts of the anvil or the side frames and anvil are clamped together by horizontal bolts which usually extend clear of the anvil itself so that there is no weakening of the latter nor any requirement for 55 bolt-receiving pockets. The side frames are provided with under-cut portions designed to coöperate with similarly formed parts of the anvil cap which, in the preferred form of my invention, is downwardly flanged so 60 as to be properly held in place. As a result, of this construction, splitting or cracking of the anvil is obviated and by means of the dowel pins or tapered anvil extensions, the 65 lifting tendency of the rebound is effectually resisted.

While I preferably use bolts 5, of the form shown, for connecting the parts of the hammer structure, it is obvious that any of the other forms of connecting means may be employed for this purpose without departing 70 from my invention.

I claim:

1. The combination in a hammer of a ram; oppositely placed side frames having guides for the ram and each having a substantially vertical clamping face; an anvil between the lower parts of the side frames; with bolts extending clear of the anvil and connecting said side frames. 75

2. The combination in a hammer of a ram; an anvil; side frames having guides for the ram and formed with substantially vertical joints between them and the anvil; and bolts connecting said parts. 80

3. The combination in a hammer of a ram; side frames having guiding means for the ram; an anvil formed to have substantially vertical joints with the anvil; and bolts engaging said frames on opposite sides of the anvil in positions to reinforce the 90 lateral strength of the latter. 85

4. The combination in a hammer of a ram; oppositely placed side frames having means for guiding the ram; an anvil; and means passing through said frames for holding said parts together, the joints between the anvil and the frames being substantially vertical. 95

5. The combination in a hammer of a ram; side frames having guides for the ram; an anvil between the lower parts of the frames, said anvil and frames being made in a plurality of parts having at least one vertical joint; with bolts extending clear of the anvil and tying said side frames together. 105

6. The combination in a hammer, of a ram; an anvil; oppositely placed side frames having guiding means for the ram; and means for holding the side frames together and to the anvil, the joints between the anvil and the frames being substantially vertical, and said frames being recessed for the reception of said anvil. 110

7. A hammer structure including a ram; an anvil and two side frames made in a plurality of parts having a substantially vertical joint or joints between them; the side frames having guiding means for the ram with means passing through and rigidly connecting the side frames to each other. 115

8. The combination in a hammer, of a ram; an anvil therefor; oppositely placed side frames having means for guiding the ram; means for holding the side frames together; a cap for the anvil; and means coöperating with the cap and the side frames for holding said cap in position. 125

9. The combination in a hammer, of a ram; an anvil therefor; oppositely placed 130

- side frames provided with means for guiding the ram and having undercut portions adjacent the top of the anvil; means for holding the side frames together; a cap for 5 the anvil fitting the under cut portion of one of the side frames; and a key coöperating with the cap and the undercut portion of the other side frame for holding said cap in position.
- 10 10. The combination in a hammer, of a ram; an anvil therefor; oppositely placed side frames having means for guiding the ram; means passing through said side frames for holding said frames together; the joints 15 between the anvil and the frames being substantially vertical; with means for preventing relative vertical movement of said parts.
11. The combination in a hammer, of a ram; an anvil therefor; oppositely placed 20 side frames having means for guiding the ram; means passing through said side frames for holding said frames together; the joints between the anvil and the frames being substantially vertical; and dowel pins 25 between the anvil and the frames for pre-

venting relative vertical movement of said parts.

12. The combination in a hammer, of a ram; an anvil therefor having vertical faces and ledges adjacent thereto; side frames 30 respectively resting on said ledges, provided with means for guiding the ram and having portions bearing against said vertical faces; with bolts connecting said frames outside of the anvil structure. 35

13. The combination in a hammer, of a ram; an anvil therefor; side frames having means for guiding the ram; means for holding said parts together; a cap for the anvil having flanges for positioning it there- 40 on; and means for retaining the cap in place.

In testimony whereof, I have signed my name to this specification, in the presence of two subscribing witnesses.

HENRY E. DERBYSHIRE.
